Primary Examiner — Jack Reickel*Assistant Examiner* — Rachel A Voorhies(74) *Attorney, Agent, or Firm* — Ralph E. Smith(57) **CLAIM**

The ornamental design for a hood for vehicle, as shown and described.

DESCRIPTION

FIG. 1 is a front perspective view of a hood for vehicle showing our new design;

FIG. 2 is a rear perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof; and,

FIG. 8 is a bottom view.

It will be understood that the broken lines shown in the drawings illustrate portions of the hood for vehicle that form no part of claimed design.

1 Claim, 6 Drawing Sheets(56)
